US0D1087707S

(12) United States Design Patent (10) Patent No.: US D1,087,707 S
(45) Date of Patent: * Aug. 12, 2025

(54) CHILDREN'S LUNCH BOX

(71) Applicant: Feng Li, Shenzhen (CN)

(72) Inventor: Feng Li, Shenzhen (CN)

() Term: 15 Years

(21) Appl. No.: 29/902,260

(22) Filed: Sep. 11, 2023

(51) LOC (15) Cl. 07-02

(52) U.S. Cl.

USPC D7/709

(58) Field of Classification Search

(57) CLAIM

The ornamental design for a children's lunch box, as shown and described.

DESCRIPTION

FIG. 1 is a perspective view of the children's lunch box showing my new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a perspective view thereof when the children's lunch box is open; and,

FIG. 10 is a perspective view thereof when the children's lunch box is open from another angle.

The broken lines depict portions of the children's lunch box that form no part of the claimed design.

1 Claim, 10 Drawing Sheets
